UNITED STATES PATENT OFFICE.

GEORGE H. KNÖCHEL, OF LANSDOWNE, MARYLAND.

GRAVE-PROTECTOR.

No. 873,052.

Specification of Letters Patent.

Patented Dec. 10, 1907.

Application filed May 15, 1907. Serial No. 373,657.

To all whom it may concern:

Be it known that I, GEORGE H. KNÖCHEL, citizen of the United States of America, residing at Lansdowne, Baltimore county, State of Maryland, have invented certain new and useful Improvements in Grave-Protectors, of which the following is a specification.

It frequently happens that in cemeteries as at present managed the markings of graves become disturbed and the identity of the deceased is completely lost, so that when relatives or friends desire to obtain a body for purposes of removal it can not be found. This condition of affairs becomes more pronounced when, as frequently happens, more than one body is placed in a single grave.

Where visitors are many and particularly where attendance is insufficient, the graves are much trampled and flower beds thereon are destroyed or damaged and must be often rebuilt and the floral decorations renewed in order to have the beds present an attractive appearance.

The present invention contemplates the provision of means adapted to be easily and quickly placed in position, whereby a grave may be permanently marked, and constitutes a fixed structure, on which the name of the deceased may be recorded. It is also adapted to receive a series of names so placed that by their relative positions the relative positions of a plurality of occupants of a single grave may be recorded.

The device to be described is of ornamental appearance and serves to maintain the outline of the mound in which floral decorations are planted and by its use the mound is supported at an elevation a short distance above the surface of the ground and out of easy reach of the feet of pedestrians. The structure is a labor saver in that it obviates the use of a grass border the trimming of which is ordinarily a large element in the maintaining of a cemetery.

The grave protector is a substantially rectangular structure, having a vertical substantially rectangular opening extending therethrough, and is composed of cement, stone, or concrete, which may be reinforced by iron frames. Three of its sides are inclined upwardly and inwardly, while the fourth is vertical and adapted to engage and coöperate with the flat face of a head-stone if such be at any time provided. The protector is placed with its bottom surface slightly

embedded in the earth in order that the supports which are provided at the head and foot may be hidden and covered. These supports are of different size and proportionate to the weight which each must bear. As they extend transversely of the grave and rest at their ends on solid earth, the protector, though frequently made of less extent than the horizontal section of the grave, may be placed on a new grave without incurring danger of settling with the new earth.

Referring to the accompanying sheets of drawings:—Figure 1 is a perspective view of the protector in position on a grave, shown in connection with a grave stone. Fig. 2 is a longitudinal vertical cross section of the protector and flower bed, showing a grave stone in elevation. Fig. 3 is a transverse vertical section of the protector, flower bed and a portion of the grave showing a grave stone in elevation.

The grave protector 1 is a frame of cement, concrete or stone, having three external lateral surfaces (2, 3 & 4) inclined upwardly and inwardly, which will be known respectively as the front or foot surface (2) and side surfaces (3, 4) and a plain vertical head or rear surface (5). The internal surfaces of the protector at the front and rear numbered 6 and 7 are vertical, while the internal side surfaces, 8 and 9, are inclined upwardly and inwardly. The foot or front top surface (12) is cut away as shown in Figs. 1 and 2 to form a name plate or recording surface (10) which is inclined forwardly and downwardly. A second surface (11) which may be used as a recording surface in case the grave contains more than one body, is located on a raised portion of the front of the protector and is inclined upwardly and inwardly parallel to the front surface. In case the grave is to be occupied by a single deceased his name will be placed on the upper recording surface (10) which will be hereafter termed the main recording surface. In case there are to be two bodies in the grave the first deceased will of course occupy the lower position therein and his name will be placed on the upper recording surface. The body of the second deceased to be placed in the grave will occupy a position above the first and his name will be placed on the front recording surface (11), which will be hereinafter termed the auxiliary recording surface. It is, of course, apparent that if more than two deceased are to occupy the grave the name of the first will be

placed on the main recording surface, while the names of those following will be placed in order beginning at the top of the auxiliary recording surface, and the positions of all the bodies therein may be thus recorded, the order of the bodies beginning at the bottom of the grave corresponding to the order of the names beginning on the main recording surface and reading down the auxiliary recording surface.

The protector is strengthened by the rectangular members 13 and 14, which are mailed in the body of the device when it is formed of cement, and about which the protector may be built when it is made of stone or marble. The transverse supporting members 16 and 17 are of sufficient length to extend across the grave and engage the solid ground on each side. These are placed slightly below the surface of the earth so as to be concealed. On these the protector rests, and though it is of an extent less than the horizontal cross section of the grave, its position is maintained constant thereby and it does not settle with the newly placed earth. The bearing surface of each support which rests upon the solid earth is preferably proportionate to the amount of weight it will have to support. In the embodiment shown the foot of the protector is heavier than the head, therefore the foot support (16) is shown of greater transverse cross section than the head support (17). The use of these supports which rest on solid earth which has not been disturbed in digging the grave, makes it possible to put the protector in place and plant flowers immediately after the burial, and have its position permanent so it will not sink.

A head-stone (18) is shown in each figure in connection with the protector, the flat front surface of the stone resting against the flat outer head surface of the protector so as to form a neat smooth engagement, and so arranged that the stone may settle without injury to or dislocation of the protector and the protector may settle without injury to or dislocation of the stone. It is not necessary that a head-stone accompany the grave protector, as the latter is a complete device in itself, designed, however, to coöperate with a head-stone if at any time such stone be provided; and this portion of the structure has the advantage that while the protector is complete without a head-stone at the same

time it admits such stone to be placed in position without disturbing the protector and coöperates therewith to produce an artistic effect.

Having thus described in detail one embodiment of my device, I do not wish to be understood as limiting myself to the details set forth.

What I claim and desire to secure by Letters Patent is:

1. A grave protector, consisting of an elongated upright frame having an opening extending vertically therethrough and adapted to inclose a mound of earth, the frame having three external lateral surfaces upwardly and inwardly inclined and at the head an external vertical surface adapted to engage a headstone.

2. A grave protector consisting of an upright elongated frame adapted to support and shape a mound of earth, the said frame having external lateral surfaces upwardly and inwardly inclined, and at the head an external vertical surface, the front top surface being cut away to form a forwardly and downwardly inclined recording surface, and an auxiliary recording surface formed of a raised portion of the front surface.

3. The combination of a grave protector and a headstone which coöperate to mark and beautify a grave, supports for both members having bearing surfaces engaging the solid earth and of an area proportionate to the weight borne thereby, the protector having a vertical head surface and the headstone having a coöperating vertical surface so as to form a neat, joint, to the end that the settling of the protector will not injure or move the stone and the settling of the stone will not injure or move the protector.

4. The combination of a grave protector and a headstone, coöperating to mark and beautify a grave, a vertical head surface on the protector and a coöperating vertical surface on the headstone, so that the settling of the protector will not injure or move the stone and the settling of the stone will not injure or move the protector.

Signed by me at Baltimore, Maryland, this 11 day of May, 1907.

GEORGE H. KNÖCHEL.
